UNITED STATES PATENT OFFICE

2,280,550

THERMAL SWITCH

Wayne C. Smitley, Cleveland Heights, Ohio, assignor to General Electric Company, a corporation of New York

Application August 12, 1939, Serial No. 289,897

2 Claims. (Cl. 250—27.5)

My invention relates in general to thermal switches, and in particular to switches employing a bimetallic element to make and break the interengagement of the switch contacts. Still more particularly, my invention relates to thermal switches of the glow discharge type in which the heat for actuating the bimetallic element is generated by a glow discharge in an ionizable medium. Such thermal switches are particularly applicable for use in connection with the starting and operating of electric discharge devices such as, for instance, fluorescent lamps of the well-known type now in commercial use.

Certain types of electric discharge devices, such as the aforementioned fluorescent lamps, employ a pair of thermionic electrodes which require a certain amount of preheating before the arc will strike therebetween. For this purpose, it is customary to interconnect the two electrodes in series across the line by means of an auxiliary switch, one form of which is a thermal switch of the glow discharge type referred to above. After the thermionic electrodes of the discharge device have been preheated to discharge sustaining temperature, the thermal switch automatically breaks the series connection of the electrodes, thus causing the arc to strike therebetween. Such switches must therefore provide a positive time-delayed circuit interruption in order to insure the preheating of the lamp electrodes. In addition, they must be capable of an exceedingly great number of makes and breaks, somewhat commensurate with the great number of times the lamps operated by such switch are likely to be turned on and off. Then, too, in some of the fixtures proposed for the mounting of fluorescent lamps, there is a limitation on the size of the auxiliary switch so that it will not interfere with the insertion of the lamp in the fixture.

One object of my invention is to provide a thermal switch of the glow discharge type which is positive and reliable in action and simple in construction.

Another object of my invention is to provide a thermal switch of the glow discharge type which is of exceptionally small size and of relatively long life.

Still another object of my invention is to provide a thermal auxiliary switch for starting and operating electric discharge devices having thermionic electrodes, said switch having relatively short and substantially equal starting and re-starting time intervals for the arc discharge in the discharge device.

A feature of my invention is the mounting of a U-shaped bimetallic strip around a wire electrode so as to surround the same, the said bimetallic strip and electrode being mounted within a small hermetically sealed tubular envelope so as to extend transversely thereof. A further feature of my invention is the provision of a wire switch contact secured to the free end of the bimetallic strip and so shaped as to provide a cam surface to thereby insure the return of the said switch contact to its normal position following the sealing-in of the switch envelope.

Further objects and advantages of my invention will appear from the following description of a species thereof and from the accompanying drawing in which:

Fig. 1 is a top view of a thermal switch comprising my invention with the switch envelope shown in section; Fig. 2 is an elevation, partly in section, of the switch shown in Fig. 1; Fig. 3 is an elevation, partly in section, taken at right angles to Fig. 2; Fig. 4 is a fragmentary perspective view of the switch shown in Figs. 1 to 3; and Fig. 5 is a diagrammatic illustration of the circuit employed for starting an electric discharge device having thermionic electrodes with the thermal switch comprising my invention.

Referring to the drawing, the thermal switch according to the invention comprises a small hermetically sealed bulb or envelope 10 preferably of glass and tubular in shape. Secured to one end of the envelope 10 in any suitable manner, preferably by cement, is a base 11 of the bayonet type, and comprising a metallic shell 12 and a bottom center contact 13 secured together by suitable insulating material 14. Obviously, if desired, the base 11 may be of the screw-threaded or any other suitable type. A pair of leading-in wires 15, 16 are electrically connected to the base shell 12 and bottom contact 13 respectively, and extend into the glass envelope 10 through a relatively short stem 17 at the base end of the said envelope. To permit the use of an envelope 10 of exceptionally short length, the said stem 17 is preferably of the type shown and described in United States Patent No. 2,128,173, issued August 23, 1938, to Arthur J. White and assigned to the assignee of the present application.

The portion of the leading-in wire 16 extending interiorly of the envelope 10 is preferably made of molybdenum wire approximately 20 mils or so in diameter, and is bent at right angles so as to provide a straight portion 18 extending transversely of the envelope in a direction towards, but somewhat spaced from, the

other leading-in wire 15. The straight wire portion 18 extends to a point closely adjacent the wall of the envelope 10 and serves as one of the switch contacts, as well as an electrode during the time the switch functions as a glow discharge device.

A U-shaped bimetallic element or strip 19 is secured at one end to the other leading-in wire 15 in such a manner as to extend transversely of the envelope 10 in substantially the same direction and the same transverse plane as the wire contact 18, so that the bimetallic element in effect partly surrounds the said wire contact. The U-shaped bimetallic strip 19 is disposed with the open end of the U facing in the same direction as the wire contact 18 extends, so that the ends of the bimetallic strip are more or less adjacent the free end of the said wire contact. The free leg portion 20 of the bimetallic strip 19 is extended a short distance beyond the other or main leg portion 21, as shown particularly in Figs. 1 and 2. The bimetallic strip 19 is preferably so arranged that the free leg portion 20 separates from the main leg portion 21 under the influence of heat.

A switch contact 22, preferably consisting of a length of molybdenum wire, is secured to the end of the free leg portion 20 of the U-shaped bimetallic strip 19 so as to extend transversely across the legs of the U and either overlie or underlie the straight wire contact 18. This wire contact 22, beyond the straight wire contact 18, is bent or offset towards the said straight wire contact as indicated at 23, the plane of the bend or offset extending substantially transversely of the straight wire contact 18. The extent of the offset 23 is preferably just sufficient to insure positive engagement with the straight wire contact 18 as the wire contact 22 is moved transversely across the contact 18 by the movement of the bimetallic element 19 when heated. The offset or bend 23 is preferably in the form of either an upright or inverted V (depending upon whether the contact 22 overlies or underlies the straight wire contact 18) so that the legs of the V act as a cam which will enable the offset to ride or spring over the contact 18. This is of particular importance during the manufacture of the switch since it permits the contact 22 to return to its normal position following the sealing-in operation, during which operation the V-shaped offset or bend 23 is drawn across and over onto the opposite side of the contact 18 as a result of the excessive heating of the bimetal 19. While I have indicated that the offset or bend 23 is preferably of V-shape, it is obvious that any other form of offset may be employed which will provide the desired result.

The heating of the bimetallic element 19 is effected by a glow discharge within the device. For this purpose, the envelope 10 is filled with a suitable ionizable gas or mixture of gases at a suitable pressure, while the bimetallic element 19 and the switch contact 18 are coated with a suitable activating material. The gas filling preferably consists of neon containing approximately 0.5 per cent of argon at a pressure of about 40 mm. of mercury, while the activating material preferably consists of magnesium which is vaporized or flashed onto the wire contact 18 and bimetallic element 19 (which act as electrodes during the time the switch functions as a glow discharge device) as well as on the inner surface of the envelope itself, as indicated at 24. The magnesium deposits or coatings within the envelope

perform two important functions; first, the deposit on the bimetallic element 19 and the wire contact 18 serves as an activating material thereon, and second, the deposit on the inner surface of the envelope 10 serves as a getter for cleaning up any impurities within the envelope, such as residual and occluded gases.

To provide the deposits of magnesium on the inner parts of the switch, a small cap or disc 25, preferably of nickel, is secured to the extended and bent end of leading-in wire 15 so as to be disposed directly above the bimetallic element 19. A small pellet 26 of magnesium is secured to the under surface of this cap in any suitable manner, such as by means of a wire net or strip welded, clamped or otherwise secured to the cap 25. After the envelope 10 has been evacuated during the sealing-in operation, the cap 25 is heated to a temperature sufficient to volatilize the magnesium pellet 26 thereon. The heating of the cap is preferably accomplished by placing the entire device within a high frequency inductive field. The volatilized magnesium deposits on the bimetallic element 19 and the electrode 18 to form a coating thereon, as well as on the inner surface of the envelope 10. The heating of the cap 25 is discontinued after the inner surface of the envelope 10 is coated with magnesium. Following the vaporization of the magnesium, the envelope is filled with the desired gaseous atmosphere and then sealed off in the conventional manner.

It will be apparent that by mounting the bimetallic strip 19 and switch contact 18 with their lengths extending transversely of the envelope 10 instead of longitudinally of the same as heretofore, the overall length of the device is reduced to a minimum. The short length of the device is further assured by the use of the short stem 17 made according to the disclosure in the White Patent No. 2,128,173 referred to above. Such a small switch is obviously desirable, and in some cases is necessary in order to enable its use in certain types of fixtures for electric discharge devices.

Fig. 5 illustrates diagrammatically the circuit preferably employed for starting and operating, by means of a glow discharge switch 10 comprising my invention, an electric discharge device such as the well-known fluorescent lamp 27 now in commercial use and having a pair of thermionic electrodes 28, 29, one at each end of the tubular lamp envelope. Referring to Fig. 5, the two leading-in wires 15, 16 of the glow type thermal switch 10 are connected by leads 30 and 31, respectively, to one end of the opposite lamp electrodes 28, 29. A small condenser 32, preferably having a capacity of about 0.006 mfd., is connected across the leading-in wires 15, 16 of the switch 10 so as to shunt the contacts thereof. The end of electrode 29 opposite to that end connected to the switch 10 is connected by lead 33 to one side of the line, while the corresponding end of the other lamp electrode 28 is connected to the other side of the line through lead 34, a choke coil or ballast 35, lead 36, a main switch 37 and lead 38. The thermal switch 10 thus serves to connect the lamp electrodes 28, 29 in series across the line.

The operation of the thermal auxiliary switch 10 is as follows: when the main switch 37 is closed, the potential across the electrodes 18, 19 within the thermal switch breaks down or ionizes the gas filling therein, thus causing a glow discharge to take place between the electrodes 18, 19.

The continuance of this glow discharge accordingly heats up the bimetallic element or electrode 19, thereby causing the free leg portion 20 of the bimetallic element to gradually deflect or separate from the main leg portion 21. The current flow through the switch 10 and lamp electrodes 28, 29 during the continuance of the glow discharge is exceedingly small, being of the order of 0.050 ampere or thereabouts. This amount of current is insufficient to cause any appreciable preheating of the lamp electrodes 28, 29. The glow discharge, and resulting movement of the bimetallic element 19, continues until the offset or bend 23 of switch contact 22 engages the straight wire contact or electrode 18, the latter being in the path of movement of the offset or bend 23. The engagement of the switch contacts 18 and 22 immediately shorts the arc path between the switch electrodes, so that the glow discharge is terminated and further heating of the bimetallic element 19 discontinued. With the switch contacts 18 and 22 in engagement, the current flow through the switch 10 and lamp electrodes 28, 29 then amounts to approximately 0.4 to 0.6 ampere, which is sufficiently high to effect a preheating of the lamp electrodes. Because of the slight lag in the movement of the bimetal behind the temperature rise, and further because of the tendency of the switch contacts to weld together (which latter condition is particularly true when the instant of contact between the switch contacts occurs at or close to that point of the cycle of current flow at which the current is a maximum), the switch contacts 18 and 22 remain in engagement with each other for a more or less extended period of approximately $\frac{1}{2}$ to $1\frac{1}{2}$ seconds or thereabouts. This time interval is sufficiently long to enable the current flowing through the lamp electrodes 28, 29 to adequately preheat the same to arc discharge supporting temperature, i. e., to the temperature at which they become sufficiently electron emissive to support an arc discharge therebetween. Upon the opening or separation of the switch contacts 18, 22, the arc discharge immediately strikes between the electrodes 28, 29 of the lamp 27, thereby shunting the thermal switch 10. The arc discharge occurs in the lamp 27 in preference to a restarting of the glow discharge in the thermal switch 10 for the reason that the breakdown potential of the gas within the lamp 27 is somewhat less than the breakdown potential of the gas within the switch 10, being approximately 50 to 60 volts for the lamp as compared to 75 to 90 volts for the switch.

Since the thermal switch 10 is shunted by the arc discharge within the lamp 27, the switch is virtually out of the circuit so that little, if any, current flows through the switch. Consequently, the bimetallic element 19 returns to its normal position, and the switch 10 is then ready to restart the lamp even while the arc discharge in the lamp 27 is still continuing. It is thus evident that the restart time of the switch 10 will be substantially the same as the original starting time, which is a highly desirable feature inasmuch as it permits the lamp to be turned off and on again without any appreciable delay in the restarting of the arc discharge within the lamp. In this connection, it has been found that the start and restart time of the glow switch 10 according to my invention, i. e., the total elapsed

time between closure of the main switch 36 and actual starting of the arc discharge within the lamp 27, is approximately $2\frac{1}{2}$ to 3 seconds or very close thereto.

5 While I have shown and described the preferred form of glow switch according to my invention, it is obvious that other modifications are possible within the scope of the invention. Thus, instead of employing a pill 26 of magnesium secured to the cap 25, the magnesium may be in the form of a strip extending over the inner surface of the bimetallic element 19 and secured thereto by suitable means, such as by a metal clamp preferably of nickel. This modified form 10 of the invention has the additional advantage of a somewhat longer life, for inasmuch as the entire quantity of magnesium is not flashed off during the flashing operation, the remaining magnesium, being located within the glow discharge, is subsequently sputtered off during operation of the switch so as to replenish from time to time the deposits on the parts within the envelope 10. A more or less continuous supply of activating material is thus supplied to the switch electrodes 18 and 19 throughout a long period of operation of the device. As a result, the operating characteristics of the device remain reasonably constant throughout the life of the device.

20 What I claim as new and desire to secure by Letters Patent of the United States is:

1. A thermal switch comprising a hermetically sealed envelope containing an ionizable gaseous filling, a pair of lead-in conductors extending into said envelope, a substantially U-shaped bimetallic electrode element secured at one end to one of said lead-in conductors, a contact member on the free end of said bimetallic element, the other of said lead-in conductors being provided with an electrode and contact portion located substantially between and extending substantially parallel to the legs of said bimetallic element to sustain a glow discharge between said bimetallic element and said electrode and contact portion, said electrode and contact portion being normally spaced from said contact member but intersecting the path of movement of a portion of said contact member.

2. A thermal switch comprising a hermetically sealed envelope containing an ionizable gaseous filling, a pair of lead-in conductors extending into said envelope, a substantially U-shaped bimetallic electrode element secured at one end to one of said lead-in conductors and being designed to open up when heated, the other of said lead-in conductors being provided with an electrode and contact portion located substantially between and extending substantially parallel to the legs of said bimetallic element to sustain a glow discharge between said bimetallic element and said electrode and contact portion, and a contact member secured to the free end of said bimetallic element and extending toward the supported end thereof beyond said electrode and contact portion where it is provided with a cam-like offset portion designed, upon abnormal heating of said bimetallic element, to engage and cross over said electrode and contact portion and to return to its normal position upon cooling of said bimetallic element.

WAYNE C. SMITLEY.
